UNITED STATES PATENT OFFICE

DAVID ROBERT YARNALL, OF PHILADELPHIA, PENNSYLVANIA, ASSIGNOR TO YARNALL-WARING COMPANY, OF PHILADELPHIA, PENNSYLVANIA, A CORPORATION OF PENNSYLVANIA

STEAM TRAP

Application filed August 6, 1926. Serial No. 127,534.

My invention relates to steam traps and particularly to methods of operating the valves of such a trap.

The main purpose of my invention is to provide for lifting of ball valves from their seats by the hammer blow of a bucket trap as distinguished from wedging the balls from their seats in previous forms.

A further purpose is to provide for displacement of ball valves upon their seats by the operating rod of a hammer blow bucket type steam trap and to operate the valves by levers between the operating rods and the valves.

15 A further purpose is to lift the balls of a ball valve bucket type steam trap by lifting wedges balanced with respect to the valves.

A further purpose is to increase the capacity of the float bucket without increasing 20 its height nor its overflow diameter.

Further purposes will appear in the specification and in the claims.

I prefer to illustrate my invention by but one form, selecting a form which is simple, 25 practical and highly desirable and which at the same time well illustrates the principles of my invention.

Figure 1 is a central vertical section of a structure embodying my invention.

30 Figure 2 is a fragmentary section taken upon line 2—2 of Figure 1 and looking in the direction of the arrows.

My invention is intended to be an improvement upon a type of valves at present in use 35 and which is shown in Charles H. Thompson application for patent Serial No. 711,344, filed May 6, 1924, and particularly to avoid the downward component of the wedge pressure present in the valve operation of this 40 Thompson form of intermittent discharge trap.

The main or lower compartment 6, having inlet 7 and clean-out plug 8 contains within it the operating bucket 9 which is enlarged 45 in diameter at its lower end to give additional flotation without enlarging its overflow diameter. The compartment is closed at the top by a flange member 11 bolted fast to the upper flange 12 of the lower compartment.

The open tube 13, preferably integral with the flange member 10, extends downwardly into and to near the bottom of the bucket 9, and has its lower end 14 serrated to avoid possible closure against the bottom of the bucket. 55

The upper surface of the flange member 10 is used to form a valve plate 15 which is bored at 16 in registration with the upper and open end of the tube 13. The valve seats 17 are set at some distance from this bore 16 60 and are equally spaced from it. Each valve seat lies within the rim 18 of a threaded bush 19.

The lever 26 pivoted at 27 in a post 28 threaded into the valve plate and for safety 65 locked there by nut 29. The inner end of the lever 26 surrounds the rod 30 and is engaged by a projection carried by the rod shown in the form of lock nuts 31 upon a thread 32. This frees the lever from direct engagement 70 with the rod and allows the rod to deliver a hammer blow to the lever and hence through the wedge to the ball valves, lifting and at the same time spreading these valves.

With this arrangement, when the bucket 75 starts to fill and sink there is no immediate engagement between the lock nuts or other projections and the end of the lever. This lever end is subsequently struck by the lower side of the lower lock nut transmitting the 80 blow simultaneously and equally to all of the balls.

The bucket is protected from direct lateral flow of the stream from the inlet 7 by a suitable baffle 33 forming the inside wall of a 85 downwardly directed inlet passage 34.

The operation is improved by providing a vent 36 through the baffle 33 from the top of the inlet passage into the main compartment and an outlet vent 37 from the main compartment 90 preferably into the tube 13 above the bucket and below the cover 10.

The screw stem 38 is provided with hand wheel 39 and packing gland 40. When 95 screwed down it engages and depresses the upper end of the rod 30 to open the valves and to hold them open as long as desired.

In operation drainage from the steam lines enters the trap at the inlet pipe 7 rising until 100 it overflows into the floating bucket 9. The

bucket begins to sink as it fills and as it does so fills with a rush causing it to sink with a rush. As the bucket starts to sink the rod 30 moves downwardly slowly with it, followed by a very rapid movement causing a hammer blow by the lock nuts upon this rod. This blow acts equally upon each of the balls, and rolls the balls laterally from their seats opening the trap to discharge.

10 Steam pressure within the trap now forces rapid discharge into and through the open notched end 14 of the central pipe 13 into the top shell and out through the uncovered ports 17 into the discharge passage 19 and thence 15 through pipe 21 to waste, emptying the bucket.

As the bucket empties it rises, floating upwardly lifting the rod and releasing the end of the lever 26 surrounding the rod. The 20 outer end of the lever being heavier than the inner end, the lever tilts in a counter-clockwise position permitting the ball valves to roll back to their positions over the valve openings. This is assisted by the weight of the 25 balls which tend to depress the outer end of the lever. When the ball valves close the openings they stop the discharge completing the cycle.

The vent 36 automatically prevents locking 30 of air or other vapor in the inlet passage 34 and the vent 37 automatically relieves air or vapor locked in the upper part of the lower compartment resulting in much better and smoother operation.

35 My construction retains the advantages of wedge action present in the structure of the Thompson application above referred to while avoiding the downward pressure upon the balls present in that construction and 40 combining wedge and lifting actions to great advantage.

In view of my invention and disclosure, variations and modifications to meet individual need or particular whim will doubtless 45 become evident to others skilled in the art, I of course intend to claim herein all such in so far as they fall within the reasonable spirit and scope of my invention.

Having thus described my invention, what 50 I claim as new and desire to secure by Letters Patent is:—

In a steam trap for intermittent discharge, a trap bucket, a compartment therefor, a plurality of spaced independent discharge valves 55 each comprising a seat and a ball adapted to roll over and away from the valve opening, a projection movable with the trap bucket, a lever having one end adapted to engage all of the balls to roll them from their seats, 60 heavier at the end which engages the balls so as normally to exert no pressure upon them, and at its opposite end coming within the path of movement of the projection and a pivot for the lever between its ends.

65 DAVID ROBERT YARNALL.
